EXPOSED PIPING GAS OUTLET

William E. Doering, Chicago, Ill., assignor to National Cylinder Gas Company, Chicago, Ill., a corporation of Delaware

Application May 20, 1954, Serial No. 30,595

Term of patent 14 years

(Cl. D52—2)

Fig. 1.

Fig. 2.

Fig. 3.

Fig. 1 is a perspective view of an exposed piping gas outlet, showing my new design.

Fig. 2 is a side view thereof slightly in perspective.
Fig. 3 is a top plan view.

I claim:

The ornamental design for an exposed piping gas outlet, as shown.
